UNITED STATES PATENT OFFICE.

GOTTHILF LEISCHNER, OF MEGARGEL, TEXAS.

PLANTER.

1,106,879.

Specification of Letters Patent. Patented Aug. 11, 1914.

Application filed December 13, 1913. Serial No. 806,503.

To all whom it may concern:

Be it known that I, GOTTHILF LEISCHNER, a citizen of the United States, residing at Megargel, in the county of Archer and State 5 of Texas, have invented certain new and useful Improvements in Planters, of which the following is a specification, reference being had to the accompanying drawings.

This invention relates to certain improvements in planters and has relation more particularly to a planter of the drill type and the object of the invention is to provide a device of this general character of a novel and improved character which may be applied with convenience and facility to the leg of an ordinary cultivator.

The invention consists in the details of construction and in the combination and arrangement of the several parts whereby certain 20 important advantages are attained and the device is rendered simpler, less expensive and otherwise more convenient and advantageous for use, all as will be hereinafter more fully set forth.

25 The novel features of the invention will be carefully defined in the appended claim.

In order that my invention may be the better understood, I will now proceed to describe the same with reference to the accompanying drawings, wherein—

Figure 1 is a view in side elevation of a planter constructed in accordance with my invention, shown in applied position, a portion of a cultivator being shown; Fig. 2 is a 35 view in side elevation and partly in section of my improved planter, taken from the side opposite to that shown in Fig. 1; and Fig. 3 is a view in top plan of my device as herein embodied.

40 As disclosed in the accompanying drawings, 1 denotes a cultivator of any ordinary or preferred type having depending rearwardly therefrom the usual beam 2, from which depends the conventional leg 3 which 45 is adapted to have affixed thereto the cultivator shovel.

4 denotes a drill or shoe of any well known type having secured at its lower end the sweep or blade 5 which serves in an 50 effective manner as a grass and weed destroyer, which is believed to be self-evident. Rested upon the upper portion of the shoe or drill 4 is the supply hopper 6 with which 55 coacts suitable planting mechanism under control of the shaft 7. As this planting mechanism or feeding mechanism, as it may

be termed, forms in its details no particular part of my present invention, it is not believed that a detailed disclosure or description thereof need be given. The upper portion of the rear of the drill or shoe 4 is provided with a vertically extended elongated slot 8 through which is adapted to pass the clamping bolt 9 which is also directed through the shovel back 10 and adapted to hold the drill in operative position, it being readily understood that the elongated slot 8 permits a ready and convenient adjustment of such shoe or drill as the requirements of practice may dictate. As is believed to be self-evident the shovel back is adapted to be secured to the leg 3 of the cultivator in the usual manner through the medium of the clamping bolt 11, as is clearly shown in the drawings.

Secured to the upper portion of the shoe or drill 4 and at opposite sides thereof are the depending curved extremities 12 of the substantially U-shaped frame 14 of predetermined dimensions which has pivotally secured thereto, as at 15, intermediate the length of the sides of such frame 14 the end portions of the upwardly directed extensions 16 of the bearing frame 17 in which is mounted the pressing wheel or roller 18.

In order that the pressing wheel or roller 18 may have the requisite tension to properly operate upon the furrow formed by the drill or shoe 4, I provide such frame 17 with the cross bar or brace 19 having the loosely directed upwardly projecting elongated member 20 disposed therethrough, which has its upper extremity suitably directed through a clevis 21 projecting rearwardly from the base of the U-shaped frame 14, hereinbefore referred to; and surrounding such member 20 and interposed between the clevis 21 and the bracing bar 19 is the expandable member 23, herein shown as in the nature of a coil spring, possessing the requisite tensile strength, it being readily perceived that the tension of such spring can be readily regulated through the action of the element 24 in threaded engagement with the lower end portion of such elongated member 20.

As herein disclosed, the shaft 7 of the delivery or feeding mechanism of the drill or shoe 4 is caused to rotate by an operative connection with the shaft 26 of the pressing wheel or roller 18 and, as herein disclosed, such connection is afforded by the sprocket

chain 27 directed around the sprocket wheels 28 and 29 suitably fixed upon the shafts 7 and 26, respectively. The feeding or delivery mechanism in the present instance is 5 of a type whereby the control of the feed is obtained through a longitudinal endwise adjustment of the shaft 7 which is adapted to be locked in its various adjustments through the medium of the set screw 30 and in order 10 to afford an additional bearing for such shaft 7, I have depending forwardly of the frame 14 the arm 31 terminating in a bearing 32, as is particularly shown in Fig. 2, and in which such shaft 7 is adapted to be 15 mounted.

While the wheel or roller 18 is adapted to press the furrow created by the drill or shoe 4, I find it of particular advantage to employ the covering chain 33 positioned in advance 20 of the wheel or roller 18 and depending from the cultivator leg 3 at a point above the shovel back 10.

It is to be particularly noted that the 25 operating mechanism for my improved drill or planter is in close proximity to the surface with which it is adapted to coact and whereby it is permitted to employ the same with convenience for planting or sowing the seed between rows of growing cotton; such 30 operating gear is positioned below the branches and foliage of the cotton plants and therefore will not tear off the same.

From the foregoing description it is 35 thought to be obvious that a planter constructed in accordance with my invention is of an extremely simple and comparatively inexpensive nature and is particularly well

adapted for use by reason of the convenience and facility with which it may be applied to the leg of any conventional cultivator and 40 it will also be obvious that my invention is susceptible of some change and modification without material departure from the principles and spirit thereof and for this reason I do not wish to be understood as limiting 45 myself to the precise arrangement and formation of the several parts herein shown in carrying out my invention in practice.

Having thus fully described my invention what I desire to claim and secure by Let- 50 ters Patent, is:

A planter attachment comprising a drill provided with a feeding means, said feeding means including a rotatable shaft projecting beyond one side of the drill, a frame 55 projecting rearwardly from said drill, an arm projecting forwardly from the frame and terminating in a bearing through which the projecting portion of the shaft of the feeding means is directed, a bearing frame 60 pivotally engaged with the first named frame, a presser roller mounted in the bearing frame, an expansible member interposed between the first named frame and the bearing frame, and means coacting with the 65 presser roller for positively rotating the shaft of the feeding means.

In testimony whereof I hereunto affix my signature in the presence of two witnesses.

GOTTHILF LEISCHNER.
